ATTORNEY

UNITED STATES PATENT OFFICE

WILLIAM M. HILLS, OF HARTFORD, CONNECTICUT

WATER HEATER

Application filed May 16, 1931. Serial No. 537,789.

This invention relates to apparatus for heating water or other liquids, and an object of the invention, among others, is the production of a heater of simple and inexpensive construction in the use of which liquid may be heated in a particularly rapid and efficient manner.

One form of a heater embodying this invention and in the construction and use of which the objects herein set out, as well as others, may be attained is illustrated in the accompanying drawing, in which—

Figure 1 is a view in elevation of my improved heater with the enclosing jacket or case removed and with parts broken away to show construction.

Figure 2 is a top view with parts broken away to show construction.

Figure 3 is a view in cross-section on a plane denoted by the dotted line 3—3 of Figure 1.

Figure 4 is a bottom view with parts broken away to show construction.

The base of my improved heater is preferably composed of three sections, a gas receiving section 6, a water inlet section 7 and a tube supporting section 8. The section 6 comprises a bottom with a flange rising therefrom creating a recess that, when closed by the section 7, constitutes a gas chamber 9. The section 7 has a hub 10 extending into the gas chamber with a water inlet 11 in the hub to which a water inlet pipe 12 is secured, said pipe extending through the gas chamber.

The passage 11 communicates with radially extending distributing passages 13, there being preferably two of these passages extending from side to side of the intermediate section and opening at the edge thereof, said

passages crossing each other at the center of the section. The ends of the passages are closed by screw plugs 14, and the sections 6 and 7 may be secured together in any suitable manner. An opening 15 is formed in the bottom of the lower sections for attachment of a gas supply tube. Three sets of gas tubes are secured to the section 7, extending completely therethrough and opening into the gas chamber 9. These tubes also extend through a central opening in the section 8

of the base, the tubes 16 of one set having tips located a short distance from the top of the section 8 of the base, the tubes 17 of another set having their tips located a little further from said section, and the tubes 18 having their tipped ends located still further from the section 8.

The tube supporting section 8 has an annular groove 19 formed in its under surface, this groove being closed by the top of the section 7, thereby constituting a passage having ports 20 opening into the passages 13, and as shown in Figure 1 of the drawing. Two concentric rows of holes 21 and 22 are formed through the section 8, each row of holes cutting into the groove 19 so that substantially one-half of each hole intersects the groove and the remaining half of each hole constitutes a recess 23 in the side of the groove. Two concentrically disposed rows 24—25 of tubes are secured in the holes 21 and 22 and rise therefrom for a considerable distance above the ends of the gas tubes 18.

The top of the structure consists of two sections, a tube receiving section 26 and a water outlet section 27 secured together in any suitable manner. The section 26 is a duplicate of the section 8 at the bottom of the structure, having rows of holes 21—22, the groove 19, the two rows of holes being arranged as in the bottom section with the recesses 23 formed in the sides of the groove 19. The section 27 is substantially a duplicate of the corresponding section 7 at the bottom of the heater, having ports 20, collecting passages 13 and an outlet passage 28 corresponding to the inlet passage 11, an outlet pipe 29 being secured to the section for delivery of water from the heater.

As hereinbefore mentioned, a jacket or case may be applied in any suitable manner to enclose the gas and water tubes, said jacket having a suitable door for access to the interior of the case for lighting, or for other purposes, and with suitable openings to provide for ventilation.

In accordance with the provisions of the patent statutes, I have described the principles of operation of my invention, together with the device which I now consider to rep-

resent the best embodiment thereof; but I desire to have it understood that the device shown is only illustrative, and that the invention may be carried out by other means and applied to uses other than those above set out.

I claim:

1. A liquid heater including a base, composed of a gas receiving section having a peripheral flange to create a recess, an inlet section resting on said flange to close said recess and thereby create a gas chamber, said inlet section having passages therein, an inlet pipe extending through said gas chamber and communicating with said passages, tubes communicating with said passages and extending upwardly from said base, means at the top of the structure for collecting liquid delivered by said tubes, and gas tubes communicating with said gas chamber and extending upwardly within the space bounded by said tubes.
2. A liquid heater including a base composed of a gas receiving section having a peripheral flange to create a recess, an inlet section resting on said flange to close said recess and thereby create a gas chamber, said inlet section having a passage extending inwardly at the center thereof and communicating with passages extending crosswise of each other across the section, an inlet pipe extending through the gas chamber into said inlet passage, ports opening out of said crosswise passages, tubes communicating with said ports and extending upwardly from said base, means at the top of the structure for collecting liquid delivered by said tubes, and gas tubes communicating with said gas chamber and extending upwardly within the space bounded by said liquid tubes.
3. A liquid heater comprising a base including a tube supporting section having an annular groove with recesses located at intervals in the side walls of the groove and holes extending into said recesses, means for delivering liquid to said groove, a gas chamber, gas tubes communicating with said chamber and rising from the base, tubes secured in said holes and rising from the base, and means at the top of the structure for collecting liquid delivered by said tubes.
4. A liquid heater comprising a base including a tube supporting section having an annular groove in its flat surface, said groove having recesses in the sides thereof with holes opening through the section into said recesses, a plate supporting said section and closing said groove, said plate having passages to deliver liquid to said groove, tubes secured in said holes and rising from the base, gas pipes rising within the space bounded by said tubes, means for supplying gas to said pipes, and means at the top of the structure for collecting liquid delivered by said tubes.
5. A liquid heater comprising a base hav-

ing a gas chamber therein and including an inlet section with passages therein, means for delivering liquid to said passages, a tube supporting section having a groove in its under surface closed by the upper surface of said inlet section, there being ports opening from the passages in the inlet section into said groove and said groove having recesses located in the side walls thereof and with holes extending into said recesses, tubes secured in said holes and rising from said base, gas pipes extending from said gas chamber upwardly within the space bounded by said tubes, and means at the top of the structure for collecting liquid delivered by said tubes. 80

6. A liquid heater comprising a base including a tube supporting section with an annular groove therein, recesses in the side walls of the groove and holes opening into said recesses, said base having a gas chamber, means for supplying liquid to said groove, means for supplying gas to said gas chamber, gas pipes communicating with said chamber and rising from the base, tubes secured in said holes and rising from the base, a tube receiving section in the top of the structure of duplicate construction to the tube supporting section at the bottom, and means at the top of the structure for collecting liquid delivered by said tubes. 90

7. A liquid container comprising a base including a tube supporting section having an annular groove with recesses located at intervals in the side walls of the groove and holes extending into said recesses, means for delivering liquid to said groove, tubes secured in said holes and rising from the base, means for heating liquid within said tubes, and means at the top of the structure for collecting liquid delivered by said tubes. 100

8. A liquid heater comprising a base including a tube supporting section having an annular groove in its flat surface with two concentric rows of holes opening through the section into said groove on opposite sides thereof, a plate supporting said section and closing said groove, said plate having passages to deliver liquid to said groove, two concentric rows of tubes in said holes and rising from the base, means for heating liquid within said tubes, and means at the top of the structure for collecting liquid delivered by said tubes. 110

9. A liquid heater comprising a base including a tube supporting section having an annular groove in its flat surface, said groove having recesses in the sides thereof with holes opening through the section into said recesses, a plate supporting said section and closing said groove, said plate having passages to deliver liquid to said groove, tubes secured in said holes and rising from the base, means for heating liquid within said tubes, and means at the top of the structure for collecting liquid delivered by said tubes. 120

10. A liquid heater comprising a base having a gas chamber therein and including an inlet section with passages therein, means for delivering liquid to said passages, a tube supporting section having a groove in its under surface closed by the upper surface of said inlet section, there being ports opening from the passages in the inlet section into said groove, and said groove having recesses located in the side walls thereof and said holes extending into said recesses, tubes secured in said holes and rising from said base, means for heating liquid within the tubes, and means at the top of the structure for collecting liquid delivered by said tubes.

11. A liquid heater comprising a base including a tube supporting section with an annular groove therein, an inlet section secured against the under surface of said tube supporting section and closing said groove and having passages communicating with said groove, means for delivering liquid into the inlet section for delivery to said groove, a top including a tube receiving section of duplicate construction to the tube supporting section of the base and an outlet section of a form to be cast in the same die as used for the inlet section of the base, said outlet section closing the groove in said tube receiving section, tubes connecting said tube supporting and tube receiving sections, and means for heating liquid within said tubes.
